INVENTOR
By Victor J. Evans
ATTORNEY

UNITED STATES PATENT OFFICE

SAMUEL S. NEWMAN, OF WINFIELD, KANSAS

ALARM

Application filed August 22, 1930. Serial No. 477,110.

This invention relates to an alarm device and more particularly to a device designed to be mounted upon a door or window frame and so constructed as to contain a blank cartridge and including, in its structure, a firing pin and means for actuating the firing pin to fire a cartridge in the event the door or window, in connection with which the device is employed, is moved to open position, although the invention is not limited to this use as the device is so constructed that it may be employed upon automobiles or in flower gardens or melon patches, or even carried in one's pocket and manually actuated, to fire the blank cartridge and thus simulate a revolver and, in all probability, frustrate an attempted hold-up.

Another object of the invention is to provide an alarm device which may be readily installed upon relatively fixed and movable parts such as a door frame and door or window frame and window without perceptibly marring the said parts.

This invention also consists in certain other features of construction and in the combination and arrangement of the several parts, to be hereinafter fully described, illustrated in the accompanying drawings, and specifically pointed out in the appended claim, it being understood of course that minor changes may be made so long as they fall within the scope of the claim.

In describing my invention in detail, reference will be had to the accompanying drawings, wherein like characters denote like or corresponding parts throughout the several views, and in which:

Figure 1 is a view partly in elevation and partly in section illustrating the device embodying the invention.

Figure 2 is a top plan view of the device, the same being illustrated as installed upon a door frame and door, shown in section.

Figure 3 is a detail vertical sectional view

on the line 3—3 of Figure 1, looking in the direction indicated by the arrows.

Figure 4 is a similar view on the line 4—4 of Figure 1.

The device embodying the invention comprises a cylindrical barrel 1 which may be made of any metal found suitable for the purpose and which is formed with a bore 2 enlarged for a portion of its length as indicated by the numeral 3 so as to provide an annular shoulder 4 to constitute a seat for the rim 5 of a blank cartridge 6. Likewise the enlarged portion 3 of the bore 2 accommodates one end of a metallic tube 7 which is fitted at its said end frictionally and snugly in the enlarged end of the bore 2 of the barrel 1 so that this end of the tube will engage against the rim 5 of the cartridge and thus hold the cartridge firmly in place.

The tube 7 is closed at its outer end as indicated by the numeral 8 and formed with a longitudinal slot 9 and a firing pin 10 which is also of metal, is slidably mounted in the tube and provided with a tapered or conical point 11 designed to strike the cap of the cartridge 6 when the firing pin is forced longitudinally in the tube.

A compression spring 12 is provided as a means for forcibly projecting the firing pin 10 and this spring is arranged within the outer or closed end of the tube 7 and bears at one end against the closed end 8 of said tube and at its other end against the inner end of the firing pin 10.

In order that the firing pin 10 may be held in retracted position in the slot 9 and the spring 12 held under tension, under normal conditions, a stud 13 is formed upon or fixed to the inner or butt end of the firing pin 10 and extends through the slot 9 and is provided with a head 14 by means of which the firing pin may be slidably adjusted in the tube and the spring 12 tensioned. The slot 9 is formed at its end which is adjacent the closed end of the tube, with two lateral

branches 15 and, as shown in Figures 2 and 4 of the drawing, the stud may be grasped by its head 14 and swung so as to rotate the firing pin 10 and bring the stud into engagement with either branch 15 of the slot 9. At this point it will be evident that when the stud 13 is displaced from engagement in either branch of the slot 9 and brought into alinement with the slot and released, the spring 12 will act automatically to impel the firing pin 10 forwardly thereby causing its point 11 to strike the cap of the blank cartridge and fire the cartridge.

At this point it will also be evident that, if the device is to be merely carried in one's pocket, the stud 13 may be actuated by finger pressure, alone. However, the invention contemplates the use of the device as a warning means to cause alarm to a burglar attempting to enter a house by way of a door or window upon which the device is installed and therefore the invention contemplates the provision of means whereby the device may be so mounted.

The means referred to above comprises a leaf spring clip 16 which is riveted or otherwise secured, at one end, as at 17, to one side of the barrel 1 and the spring is offset as indicated by the numeral 18, so as to provide a portion 19 which extends in spaced relation to the side of the barrel 1, and, in connection with this clip, there may be employed an ordinary staple 20 which, as is shown in Figure 3, may be driven into one side of a door frame 21. In thus mounting the barrel, care is taken to so position the same with respect to the door opening of the door frame that the tube 7 will extend in spaced relation to the door, which is indicated by the numeral 22, as shown in Figure 2 of the drawing and a flexible element, such as a piece of cord, indicated by the numeral 23, is tied at one end as at 24, to the stud 13 and tied at its other end as at 25 to a pin or the like, indicated by the numeral 26, which may be pressed by one's thumb or driven into the face of the door 22 and, it will be evident, from the foregoing that when the door is opened, a pull will be exerted upon the member 23 resulting in the stud 13 being swung and brought into alinement with the slot 19 thereby permitting the spring 12 to act to impel the firing pin 10 into firing contact with the cap of the blank cartridge.

What I claim is:

An alarm comprising a barrel having a bore leading in from one end and a counter-bore leading in from the opposite end said bores being concentric and the counter-bore being of greater diameter than the bore whereby a shoulder is provided interiorly of the barrel at the inner ends of the bores, the counter-bore being threaded, a tube having an exterior thread adapted to engage the thread of the counter-bore, said tube

having a passageway substantially of the same diameter as the bore and adapted to aline with the bore of the barrel when inserted therein, said tube having an angle slot, a pin slidably mounted in the tube, said pin being substantially of the same diameter as the bore, a spring interposed between the outer end of the pin and the outer end of the tube and a stud mounted upon the pin and disposed through said slot.

In testimony whereof I affix my signature.

SAMUEL S. NEWMAN.
